UNITED STATES PATENT OFFICE.

ANTONIO PARRELLA, OF WASHINGTON, DISTRICT OF COLUMBIA.

INSECT GUARD.

Application filed November 10, 1921. Serial No. 514,361.

To all whom it may concern:

Be it known that I, ANTONIO PARRELLA, a citizen of the United States, residing at Washington, in the District of Columbia, 5 have invented certain new and useful Improvements in Insect Guards, of which the following is a specification.

This invention relates to an improvement in insect guards and has particular reference to such a device adapted to be used in conjunction with the leg of an article of furniture, such as a bed, table or other article that it is desired to protect.

An object of the invention is to provide 15 such a device which may be applied to the leg of a piece of furniture without the necessity of making alterations thereon, and which will present a neat appearance.

A further object of the invention is to 20 provide an article of manufacture of the above mentioned character which is so designed as to be used in conjunction with a well known caster now upon the market.

A still further object of the invention is 25 to provide such a guard, which is so constructed, that when the furniture is given a sudden movement, the liquid contained therein will be prevented from overflowing the sides thereof.

30 A still further object of the invention is to provide such a device which is extremely simple in construction, strong, durable and highly convenient in use.

Other important objects and advantages 35 of the invention will be apparent during the course of the following description.

In the accompanying drawings,

Figure 1 is a perspective view of the 40 lower end of a leg of furniture illustrating the invention applied thereto,

Figure 2 is a side elevation thereof,

Figure 3 is a plan view of the guard, and

Figure 4 is a transverse section through 45 the guard, showing the caster in elevation.

Referring to the drawings in detail, the 50 numeral 5 designates a leg of furniture, in this instance being the leg of a bed.

The guard is formed in a cup shape, having 55 a raised central portion 6 and a cup or bowl 7. The central portion 6 extends substantially above the edge of the cup 7. The edge of the cup 7 is turned slightly in as shown at 8. The central portion 6 is provided with an aperture 9 in the center thereof, for the reception of a stem 10 carried by a caster 11. The caster in this instance

is shown as a ball caster, having a cylindrical body portion 12 and a ball bearing 13. The caster construction is common to a well known make now upon the market. The 60 stem 10 after passing through the aperture 9, enters the usual socket in the leg of the furniture. The body portion 12 when engaged with the guard, fits snugly within the central portion 6, and such fit is sufficiently tight to prevent the caster from dropping out, should the furniture be lifted. When it is desired to use this guard upon the legs of other pieces of furniture, such as an ice box, that is not provided with roller means, such guard is secured to the leg by means of screws, passing through opening 14 formed in the top of the portion 6 of the guard. 65

In operation, when it is desired to place 70 the guard upon a leg of an article of furniture, the caster is forced into the central portion 6, with its stem 10 projecting above the guard. As before mentioned, this fit

should be a snug one, and one that requires 75 a small amount of pressure to assemble. The stem is then inserted into the usual socket in the leg, provided for this purpose. Any suitable means may be employed to hold the stem in the socket of the furniture, 80 as this is common practice, and applicant makes no claim thereto. After the guard has been placed upon the leg, same is filled to about the point indicated with some insecticide. Should the bed be given a sudden 85 movement, the liquid contained in the cup will be prevented from splashing by coming into contact with the inturned edge 8, which sets up a backwash in the direction of the central portion and as the portion 6 extends above the cup 7, the liquid will be prevented 90 from coming in contact with the leg of the furniture. 95

It will be obvious from the foregoing 100 that an extremely simple form of insect guard has been provided, one that presents a neat appearance and one that may be conveniently applied to furniture and at the same time use a caster now manufactured and for sale upon the market. 105

The guard as described is adapted to be 110 stamped or pressed from a single piece of metal, thereby making its manufacture extremely cheap, and it is highly important that a caster of the type shown be used, as it is well known that the roller casters now in use are very destructive to a carpet or

floor. The ball bearing caster shown has proven itself satisfactory and is more preferable than the roller.

It is to be understood that the form of the invention herewith shown and described is to be taken as the preferred form thereof, but is to be understood that various changes in the shape, size and arrangement of parts may be resorted to without departing from the spirit of the invention or the scope of the subjoined claim.

Having described my invention, what I claim is:

In an insect guard for the legs of articles of furniture, the combination with an element of stamped sheet metal comprising a cup shape portion for holding an insecticide and a centrally disposed portion of inverted cup shape with an opening in its top, said inverted cup shaped portion ex-

tending substantially above the upper edge of the first named cup shaped portion, of a caster comprising a rotative ball and a cylindrical body portion within which said ball is housed and rotates, the external surface of the cylindrical body portion corresponding both as to size and shape to the internal surface of the inverted cup shaped portion throughout the height of the latter, said body portion of the caster being completely housed within said inverted cup shaped portion and held tightly therein by frictional engagement with the inner wall of the said inverted cup shaped portion, said caster comprising a stem which passes through the opening in the top of the inverted cup shaped portion.

In testimony whereof I affix my signature.

ANTONIO PARRELLA.
